HAM HANGER

Filed Feb. 21, 1930

Inventor

W. J. Vinson

Watson E. Coleman
Attorney

UNITED STATES PATENT OFFICE

WAYLAND J. VINSON, OF PORTSMOUTH, VIRGINIA

HAM HANGER

Application filed February 21, 1930. Serial No. 430,347.

This invention relates to a ham hanger, and it is an object of the invention to provide a device of this kind which can be employed to effectively support a ham within a smoke house or for display within a store or otherwise as may be desired and in a manner whereby the hock of the ham is downwardly disposed, this eliminating the liability of grease dripping.

10 It is also an object of the invention to provide a device of this kind which supports a ham in a manner whereby air, smoke or the like may circulate substantially entirely therearound.

15 The invention consists in the details of construction and in the combination and arrangement of the several parts of my improved ham hanger whereby certain important advantages are attained and the device

20 rendered simpler, less expensive and otherwise more convenient and advantageous for use, as will be hereinafter more fully set forth.

The novel features of my invention will hereinafter be definitely claimed.

25 In order that my invention may be the better understood, I will now proceed to describe the same with reference to the accompanying drawings, wherein:—

Figure 1 is a view in front elevation of a 30 hanger constructed in accordance with an embodiment of my invention;

Figure 2 is a sectional view taken substantially on the line 2—2 of Figure 1;

Figure 3 is a sectional view taken substantially on the line 3—3 of Figure 2;

Figure 4 is a sectional view taken substantially on the line 4—4 of Figure 1.

As herein disclosed, my improved hanger comprises two side members 1 converging 40 one toward the other with the divergent extremities connected by a cross member 2. The members 1 and 2 are preferably formed from a single length of strap metal and such material is suitably bent, as at 3, to provide 45 the desired assembly or relation of the members 1 and 2.

In practice, the member 2 is at the upper portion of the device and said member 2 at its longitudinal center is provided with an up- 50 standing arm 4 to provide a suspending

means, said arm 4 being herein disclosed as provided with an opening 5 to permit the arm 4 to be readily engaged with a hook or other desired supporting member.

The lower or convergent extremities of the 55 members 1 are tied or connected by a cross member 6 and are further connected by an outstanding loop member 7. The loop member 7 and the cross member 6 are substantially coplanar and the extremities of the cross 60 member 6 and loop member 7 are secured to the adjacent end portions of the members 1 by the common fastening members 8, such as rivets. The loop member 7 is adapted to snugly receive hock portion 9 of a ham H, 65 as indicated by broken lines in Figure 2, while the central or upper enlarged portion of such ham is received within a second loop member 10, the extremities of which terminating in inwardly disposed feet 11 riveted 70 or otherwise secured, as at 12, to the members 1 at a point preferably slightly above the longitudinal centers of the side members 1.

The lower or convergent extremities of the 75 side members 1 are continued to form the rearwardly directed lugs or feet 14 which, when the device is suspended from a wall, as in a smoke house, assures the device together with the applied ham being spaced from such wall so that an effective circulation of smoke 80 may be had around the ham to assure proper curing. This spacing of the device and ham from a wall or the like is also of advantage in connection with store display or the like as it assures free circulation around the ham. 85

From the foregoing description it is thought to be obvious that a ham hanger constructed in accordance with my invention is particularly well adapted for use by reason of the convenience and facility with which it 90 may be assembled and operated, and it will also be obvious that my invention is susceptible of some change and modification without departing from the principles and spirit thereof and for this reason I do not 95 wish to be understood as limiting myself to the precise arrangement and formation of the several parts herein shown in carrying out my invention in practice except as hereinafter claimed.

I claim:—

A ham hanger comprising spaced side members, means for connecting the opposite end portions of the side members to maintain the same in desired relation, supporting means carried by one end portion of the device, and outstanding loop members carried by the side members, one of said loop members being of a size to receive the hock 10 of a ham and the other of a size to receive the upper portion of the ham, the extremities of the side members remote from the supporting means being provided with lugs disposed in a direction opposite to that of the loop 15 members.

In testimony whereof I hereunto affix my signature.

WAYLAND J. VINSON.
